UNITED STATES PATENT OFFICE.

EDWARD ELIAS, OF BROOKLYN, NEW YORK.

HAND BAG.

Application filed November 8, 1926. Serial No. 147,068.

The present invention is capable in its broader aspects of a wide range of utility, but finds its preferred embodiment in a lady's hand bag of the envelope type.

5 The so-called envelope bags usually include a single length of material providing a front section, back section and flap, the lateral edges of the front and back section being connected by gussets. A common disadvantage of this type of bag is the fact 10 that there is always a small amount of space left between the top of the gussets and the flap when the flap is folded over and buttoned, consequently small articles such as 15 change or keys may be readily lost from the bag if the latter is inadvertently inverted or carelessly handled.

A primary object of the present invention is to overcome this difficulty and provide an 20 envelope bag so constructed that there is no danger of losing the contents of the bag no matter how the bag is carried or how carelessly it is handled, providing the flap is retained in closed position.

25 Preferably this object is accomplished by the use of a novel type of gusset, the upper portion of which is extended to fill the space between the upper edge of the pocket and the flap. Preferably also, means is provided for causing the folding of the gusset, or rather the folding of the upper portion thereof in a peculiar manner which will 30 assure the proper positioning of the extended upper edge of the gusset at all times.

35 Other objects of the invention are to provide a hand bag of the general character above noted which will be of simple practical construction, rugged durable and efficient in use, neat and attractive in appearance, and 40 well suited to the requirements of economical manufacture.

With the above noted and other objects in view, the invention consists in certain novel features of construction and combinations 45 and arrangements of parts, as will be more fully hereinafter set forth and pointed out in the claims. The invention may be more fully understood from the following description in connection with the accompanying drawings, wherein—

Fig. 1 is a view in front elevation of a hand bag embodying the present invention, with one side of the flap broken away for the sake of clearness.

55 Fig. 2 is an edge view of Fig. 1.

Fig. 3 is an enlarged transverse sectional detail on the line 3—3 of Fig. 1.

Fig. 4 is a plan view of the gusset with the dotted lines indicating the position of a reinforcing member which may be used. 60

Fig. 5 is a view similar to Fig. 3, but showing the device with the reinforcing member in place.

Fig. 6 is a plan view of the reinforcing member. 65

The hand bag illustrated is of the envelope type including a front section 10, rear section 11 and cover flap 12 forming a continuation of the upper end of the rear section 11 and adapted to be folded over the face of 70 the front section 10 and secured thereto as by a fastener 13. In accordance with the conventional practice, the front section, rear section and flap, may if desired be formed of a single sheet of material. To permit the 75 relative expansion and contraction of the pocket 14 defined by the front and rear section of the bag, and to close the ends of said pocket, there are provided gussets 16 having their lateral edges sewed as at 17 to the 80 lateral edges of the front and rear sections 10 and 11. The lower ends of these gussets normally fold inwardly along a median folding line indicated at 18 and their upper ends fold inwardly along diverging fold lines indicated at 19. Thus, the main portion of the 85 gusset folds inwardly and a small V-shaped section at its top folds outwardly along a median line 28 coincident with the lower folding line 18. If the gusset is properly designed with the relatively narrow lower end 90 illustrated, and the relatively wide upper end, this folding will be the natural folding of the gusset and need not occur along sharply defined lines. 95

The upper edge of the gusset instead of running approximately straight across as is customary in the art, inclines upwardly as at 22 from opposite ends thereof, and at its intermediate portion is formed with an arcuate upwardly extending edge 20 defining a flap or tongue 21 disposed above the upper edge of the front section 10 of the bag and closing the space between said edge and the flap when the flap is closed as indicated in 100 Fig. 1, whereby to prevent the passage of small articles through the spaces under the ends of the flap when the bag is inverted or carelessly handled.

105 In order to insure absolutely accurate 110

1 folding of the gussets, so that the tongue 21 will always be approximately in contact with the lateral edges of the flap, where the latter crosses the open top of the pocket 14, I may 5 if desired, utilize a reinforcement and folding guide. This reinforcing member is illustrated in Figures 5 and 6, and its position relatively to the gusset is shown in Fig. 4. The reinforcement designated generally by 10 the reference character 25 may be of cardboard or any other suitable material, and its upper edge is shaped in conformity with the upper edge of the gusset. Slots 26 intersecting the upper edge of the member 25 15 at the junction of the shoulders 22 and the ends of the curved edge 20, converge downwardly along the lines of the proposed folds 19, and the reinforcing member is also provided with a central fold line 28 upon which 20 the central section between the slots 26 is adapted to break outwardly.

25 The distance to which the reinforcing member will extend downwardly from the top of the gusset, is determined of course by the proportions of the latter, but in any event, the reinforcement will terminate approximately at the upper end of the line 18 upon which the lower portion of the gusset folds inwardly.

30 This reinforcing member is secured in proper position between the gusset and the bag lining 30 preferably by the lines of stitching 17. The slots 26 and the fold line 28 define natural folding lines which guide the folding of the gusset, and insure the proper positioning of the tongue 21 every time the bag is collapsed and closed. Any tendency of the gussets to fold along other lines, is resisted by the relatively stiff cardboard at both sides of the slots 26 and between the slots.

45 Obviously, various changes and alterations might be made in the general form and arrangement of parts described without departing from the invention. Hence I do not wish to limit myself to the details set forth, but shall consider myself at liberty to make such changes and alterations as fairly fall within the spirit and scope of the 50 appended claims.

I claim:

1. An envelope hand bag including a front section and a rear section connected at their lower edges, gussets connecting the lateral edges of said sections and cooperating therewith to form a pocket, a flap attached to the upper edge of the rear section and adapted to be folded over the face of, and secured to the front section, the upper ends 60 of said gussets being extended to block the passage of small articles from the upper corners of the pocket under the flap, said extended upper end of the gusset folding inwardly along diverging fold lines and outwardly on a central fold line.

2. An envelope hand bag including a front section and a rear section connected at their lower edges, gussets connecting the lateral edges of said sections and cooperating therewith to form a pocket, a flap attached to the upper edge of the rear section and adapted to be folded over the face of, and secured to the front section, the upper ends of said gussets being extended to block the passage of small articles from the upper 70 corners of the pocket under the flap, the intermediate portion of the upper edges of the gussets curving symmetrically upwardly from each side to define a central blocking tongue. 80

3. An envelope hand bag including a front section and a rear section connected at their lower edges, gussets connecting the lateral edges of said sections and cooperating therewith to form a pocket, a flap attached to the upper edge of the rear section and adapted to be folded over the face of, and secured to the front section, the upper ends of said gussets being extended to block the passage of small articles from the upper 90 corners of the pocket under the flap, the lower portions of the gussets folding inwardly on a central line, and the upper portions of the gussets folding inwardly on a pair of diverging lines. 95

4. An envelope hand bag including a front section and a rear section connected at their lower edges, gussets connecting the lateral edges of said sections and cooperating therewith to form a pocket, a flap attached to the upper edge of the rear section and adapted to be folded over the face of, and secured to the front section, the upper ends of said gussets being extended to block the passage of small articles from the upper 100 corners of the pocket under the flap, the lower portions of the gussets folding inwardly on a central line, and the upper portions of the gussets folding inwardly on a pair of diverging lines, a relatively stiff reinforcing member secured to the gussets and slotted to direct the folding of the upper 105 portions of the gussets along the desired lines. 110

5. A bag as described in claim 4, and 115 wherein the reinforcing members are of cardboard and concealed between the inner faces of the gussets and the lining of the bag.

6. In a foldable container including a 120 gusset, means for directing and determining the lines along which the gusset folds, comprising a relatively stiff reinforcing member laid against the gusset and having slots therein on which the member breaks or folds 125 as the gusset is collapsed.

7. A hand-bag substantially as described 130 having a front section and a rear section connected at their lower edges, a flap attached to the upper edge of the rear section and

adapted to be folded over the face of and be secured to the front section, and gussets connecting the lateral edges of the front and rear sections and said gussets having at their upper ends or ends corresponding to the open mouth of the bag, folds arranged midway between the front and rear edges of the gussets, said folds extending from a point mid-way between the upper and lower

ends of the gussets and formed on diverging lines from their lower to their upper ends, with the upper ends of the folds extended above the upper edges of the front and rear sections in such manner that the gussets underlie and bear against the flap when the latter is in closed position, as and for the purposes set forth.

EDWARD ELIAS.
